UNITED STATES PATENT OFFICE.

GEORGE F. JACOB, OF EVANSTON, ILLINOIS.

AUTOMOBILE LAMP.

Application filed March 17, 1927. Serial No. 176,134.

This invention pertains to improvements in automobile head lights. More particularly it has reference to an arrangement of light reflecting surfaces disposed in a peculiar manner within a lamp body.

The main object of the invention is to so arrange a light reflecting surface in an automobile lamp that the light rays will be cast mainly at an angle downwardly upon the road rather than in a horizontal direction, or in an upward direction.

Another object is to provide a single reflector unit preferably of stamped metal that may be installed in any lamp body by which the advantages of my system may be derived.

The above objects and the advantages to be had will be explained fully in the following specification aided by the accompanying drawing wherein—

Figure 1 is a longitudinal sectional elevation of an automobile lamp constructed according to my invention.

Figure 2 is a front elevation of the same.

Figure 3 illustrates in perspective a one piece reflector constructed according to my invention, and

Figure 4 is a longitudinal sectional elevation of parts of a lamp body and reflector illustrating means for securing the reflector in position on said body.

In the figures the character 1 denotes a lamp body or casing which in this instance is of the so called "drum" type which includes the usual lens 2 closing the front and held in place by any form of ring or collar 3.

A reflector is mounted within the casing consisting of a dished portion 4 of any one of the general forms, or parabolic, the same being mounted upon the floor of the body 1 as denoted in Figure 1 and in a way to be described later. The front side of the said portion 4, or that lying nearest the lens 2 is, however, constructed with a vertical wall 5 or a wall the plane of which parallels the axis of the said portion, lying quite close to said axis and consequently close to the lamp 7. Said wall may include an extension to lie opposite the filament of the lamp so as to prevent the rays of the same passing through the lens 2.

Extending from the rear edge of the portion 4, or that directly opposite the wall 5 is a flat reflector portion 8 which is an integral part of the whole. Said reflector portion is designed to lie at an angle of sub-

stantially 45° to the longitudinal axis of the body 1 and at an angle to the axis of the portion 4 as may be seen in Figure 1. In order that said portion 8 may present a neat appearance it preferably must conform to the cylindrical wall of the body 1. This requires, of course, that it shall partake of a somewhat elliptical form of outline due to the fact that it has an angular position with respect to said body. Viewed from the front, therefore the edge of that portion will abut against the cylindrical wall of the body in a neat and snug manner.

In Figure 4 is shown a structure of simple but effective form for securing the reflector unit in place. The portion 4 is perforated as usual at 9 and the body 1 is perforated at 10 and through these is inserted a tubular flanged member 11. The flange member engages upon the portion 4 while a nut 12 screwed upon the member serves to clamp the parts firmly together. A tube 13 is slidable in the member 11 and may be secured by a screw 14 in the latter, the base of the lamp being held in any usual manner in said tube. This provides for easily placing the reflector unit in position and firmly securing it in place.

The portion 8 of the reflector may be held in any suitable manner at its upper free edge and it may be adjusted to any desired angle by bending it at its place of joining with the portion 4.

It is observed that the light rays are reflected mainly downward at an angle through the lens 2, and none are reflected upwardly. The refection of the lamp filament upon the portion 8 is well up toward the top edge of that member and due to the fact that said edge of the portion 8 is stationed somewhat back from the lens 2 the lamp's image will not shine in the eyes of an oncoming driver whose eye is well above the reflector, and especially since a slight downward tilting of the lamp body or casing 1 can be resorted to.

As arranged, practically all of the light is reflected from the portion 8 and it is thrown upon the road at a greater or less distance in front of the vehicle depending upon the tilt of the portion 8, the tilt of the lamp body, or both.

There is no glare of light at any single point but rather a flat and even distribution thereof. Since the wall 5 of the portion 4

is vertical and close to the lamp 7 few if any rays will be reflected therefrom against the portion 8.

I claim:

- 5 As an article of manufacture, a reflector unit formed from a single piece of metal comprising a portion of a segment of a hollow spherical body part of which is a straight wall paralleling its axis forming
- 10 one of the reflecting portions of said body,

and having an opening in its wall at said axis, said segment including an integral flat reflector portion extending from that edge thereof directly opposite the said straight wall and overhanging said opening, the said flat reflector portion and the said straight wall lying at opposite sides of the body. 15

In testimony whereof I affix my signature.

GEORGE F. JACOB.
